UNITED STATES PATENT OFFICE.

ARTHUR M. ALDRICH, OF WATERVLIET, NEW YORK, ASSIGNOR TO VACUUM SEAL COMPANY, INC., OF NEW YORK, N. Y., A CORPORATION OF DELAWARE.

CLAMP FOR PRESERVING-JAR COVERS.

Application filed January 24, 1925. Serial No. 4,558.

To all whom it may concern:

Be it known that I, ARTHUR M. ALDRICH, a citizen of the United States, residing at Watervliet, in the county of Albany and 5 State of New York, have invented new and useful Improvements in Clamps for Preserving-Jar Covers, of which the following is a specification.

This invention relates to a preserving jar 10 usually of glass, having a compressible rubber gasket surrounding its mouth, and a cover, also usually of glass, adapted to be seated on the gasket.

In particular, the invention relates to a 15 vacuum jar, the cover of which is adapted to be confined on the gasket by atmospheric pressure, caused by exhaustion of air from the jar by an air pump, when the cover is located over the gasket, the cover being 20 pressed by the atmosphere against the gasket when a sufficient vacuum is produced in the jar. The invention is not limited, however, to use with a so-called vacuum jar, and may be used with any jar having 25 a compressible gasket, on which a cover is seated.

The object of the invention is to provide a simple and effective cover clamp, adapted 30 to secure the cover in place by mechanical pressure, so that when applied to a vacuum jar, sealed by atmospheric pressure, liability of unsealing by a release of the vacuum is prevented.

Of the accompanying drawings forming a 35 part of this specification,—

Figures 1 and 2 are side views, showing a portion of a jar, its cover, and a clamp embodying the invention.

Figure 3 is an enlarged section on line 40 3—3 of Figure 1.

Figures 4, 5 and 6 show separately the parts hereinafter called the holder, the slide and the lever.

The same reference characters indicate the 45 same parts in all of the figures.

12 designates the jar, 13 the cover, and 14 the rubber gasket interposed between the cover and a seat 15, surrounding the mouth of the jar, these parts being of any suitable 50 form and construction. The jar is provided, as heretofore, with a downwardly facing peripheral shoulder 16, below its mouth.

My improved clamp comprises a wire ring 17, adapted to encircle the jar below the shoulder 16, the ring being con-

fined against upward movement by the shoulder, a pair of holders 18, each of which is preferably a flat sided metal plate, and includes a hinge socket member 19, engaged with the ring 17, which constitutes a hinge pintle member, the holder being adapted to swing toward and from the periphery of the jar. Each holder 18 includes also a cam abutment 20, on the swinging end, a longitudinal slot 21, between the hinge member and the abutment, and a pair of slide guides 22 at opposite edges of the holder. The holders 18 are hinged to diametrically opposite portions of the ring 17. 70

The clamp also comprises a pair of slides 23, movable on the holders 18, between the guides 22, and provided with hooks 24, adapted to bear on diametrically opposite portions of the cover 13, and with headed 75 studs 25, extending through, and movable in the slots 21.

Finally the clamp comprises a pair of levers including cams 26, having orifices 27, receiving the holder studs 25, and lever arms 80 28, projecting from the cams. The perimeters of the cams are eccentric to the orifices 27, so that the cams are eccentrically mounted on the studs, their perimeters bearing on the abutments 20. 85

The arrangement is such that when the lever arms 28 are turned downward, the cams are caused to depress the slides 23, so that the hooks 24 exert clamping pressure on diametrically opposite portions of the cover 90 13, and when the lever arms are turned upward, the hooks release the cover.

The heads of the studs 25 confine the slides 23 against the holders, so that the slides swing sidewise with the holders to locate the 95 hooks over and remove them from the top of the cover. At the same time, the guides 22 prevent the slides from swinging edge-wise on the holders.

As shown by Figures 4, 5, and 6, each 100 holder, slide, and cover lever is made from a single metal plate, the only added parts being the studs 25, which may be secured to the slides 23, in any suitable manner.

The perimeter of each cam 26 is provided 105 with a plurality of flat faces, each adapted to have an elongated bearing on the corresponding abutment 20, and thereby retain the cam in various positions.

As shown by Figure 6, each cam has a flat 110

face 30, arranged to bear on the corresponding abutment 20, when the lever arm 28 is turned downward, as shown by Figures 1 and 2. When the cam is in this position, 5 the cover is fully closed and operatively sealed.

The cam also has two flat faces 31, either of which may bear on the abutment, when the lever arm is turned to a position at right 10 angles to that shown by Figures 1 and 2. When a face 31 bears on the abutment, the cover is only partly closed, and not operatively sealed.

In other words, the cover is securely held 15 in position to effect a partial seal, when the filled jar is being subjected to preliminary boiling heat. The partial seal allows the escape of steam and air from the jar. After this escape the lever arm 28 is turned down- 20 ward to the position shown by Figures 1 and 2, and the jar is completely sealed.

I claim:

1. A cover clamp comprising a ring adapted to encircle a jar below the mouth thereof, and below a downwardly facing peripheral shoulder on the jar, a pair of holders 25 hinged to the ring at diametrically opposite portions thereof, each holder including a hinge member engaged with the ring, a 30 cam abutment at the swinging end of the holder, a longitudinal slot between said

hinge member and abutment, and slide guides at opposite edges of the holder; a pair of slides movable on the arms between said guides, and provided with hooks, 35 formed to bear on the top of the cover, and with studs extending through, and movable in, the holder slots, and a pair of levers including cams eccentrically mounted on said studs, and bearing on said abutments, 40 and arms projecting from the cams, the arrangement being such that when the lever arms are turned downward, the cams are caused to depress the slides, so that their hooks exert clamping pressure on diametrically opposite portions of the cover top, and when the lever arms are turned upward, the hooks release the cover, the holders and slides being adapted to swing sidewise toward and from the cover, and the guides 45 preventing the slides from swinging edge-wise on the holders.

2. A cover clamp as specified by claim 1, each cam being provided with a plurality of flat faces, one arranged to bear on the abutment when the cover is fully closed, while another is arranged to bear on the abutment when the cover is partly closed.

In testimony whereof I have affixed my signature.

ARTHUR M. ALDRICH.
